COMBINED POURING AND SIFTING CONTAINER

William F. Punte, Syracuse, N. Y., assignor to
 Continental Can Company, Inc., New York,
 N. Y., a corporation of New York

Application February 9, 1934, Serial No. 710,559

1 Claim. (Cl. 221—64)

The invention relates to new and useful improvements in a combined pouring and sifting container for condiments, such as spices and the like.

5 An object of the invention is to provide a container having an opening in one of the ends thereof with which is associated a rotary closure disk having a pouring opening and sifter openings, which closure disk is also provided with a 10 spout disposed so that when the pouring opening is uncovered the spout will project over the side seam of the container for directing the contents passing through said pouring opening over and away from said end seam.

15 In the drawing:

Fig. 1 is a plan view of the container embodying the improvements.

Fig. 2 is a view partly in side elevation and partly in vertical section through the upper portion 20 of the container.

Fig. 3 is a plan view of the container with the closure disk positioned for sifting.

Fig. 4 is a view similar to Fig. 3 but showing the closure disk positioned for closing all of the 25 openings and placing said spout so that it is housed beneath the extreme outer edge of the double seam.

Fig. 5 is a sectional view on the line 5—5 of Fig. 4.

30 The container embodying the invention includes a body portion which is preferably rectangular in cross section with rounded corners. There is a closure end secured to the body portion at each end thereof by double seaming. 35 One of these end closures is provided with a conical depression extending inwardly and with the bottom wall of said depression inclining upwardly toward the side seam at one side of the container and with its extreme upper portion substantially 40 in the plane of the closure end. There is an opening through this bottom wall of the depression and pivotally mounted on the outer face of said bottom wall is a closure plate having an opening adapted to be brought into register with the opening in said bottom wall. The closure plate is also provided with sifter openings located at each side of the pouring opening and there is a spout attached to the closure plate in the region of the pouring opening and this 45 spout projects upwardly and outwardly from the plate. The bottom wall of the depression is so inclined and the spout so formed that when the pouring openings are freed, said spout projects upwardly over the end seam so as to discharge 50 the contents over and away from the end seam.

On the other hand, when the openings are all closed, the extreme outer end of the spout lies beneath the plane containing the extreme upper end of the end seam.

5 Referring more in detail to the drawing, the container embodying the improvements, includes a body portion 1, to which a lower end closure is secured by a double seam 2. An upper end closure 3 is likewise secured to said body portion 1 by a double seam 4. The end closure 3 is inset 10 the height of the double seam.

Said end closure 3 is provided with a depression forming a bottom wall 5 and side walls 6. The side walls are preferably conical. The bottom wall 5 of the depression inclines from the point 15 7 upwardly to the point 8 and the point 8 is adjacent the end seam 4 at one side of the container. This end wall substantially vanishes into the closure end at the point 6. There is a pouring opening 9 through the bottom wall of the depression, which opening is curved at its outer and inner edges substantially concentric with the outer edge of the circular bottom wall of the depression. The side edges of the opening 9 are 20 preferably radial of the bottom wall of the depression. 25

Mounted on this bottom wall of the depression is a closure disk 10. The closure disk 10 is circular in outline and is provided with a central opening 11. The bottom wall of the depression is 30 provided with struck-up lugs 12, 12, which extend up through this opening 11 and are folded down onto the outer face of the closure disk. This serves as a means for supporting said closure disk so that it may be rotated about the 35 center of the bottom wall of the depression. Said closure disk is provided with an opening 13 which conforms in shape and size to the pouring opening 9 in the bottom wall of the depression. The closure disk is also provided with a series of small 40 openings 14 at one side of the opening 13 and a series of small openings 15 at the other side thereof. These openings 14 and 15 are so disposed that one or the other thereof may be brought into register with the pouring opening 45 9. When the opening 13 is in register with the opening 9, the contents of the opening may be poured or dredged through the two openings and when either the openings 14 or 15 are in alignment with the opening 9, then the contents may 50 be sifted through these openings.

In Figure 1 of the drawing, the openings 9 and 13 are in register and the closure plate is set for dredging. In Figure 3 of the drawing, the openings 15 are in alignment with the opening 9 and 55

the closure disk is set for sifting through said openings. In Figure 4 the closure opening is shown as turned to a position wherein the openings 13, 14 and 15 are out of register with the opening 9 and the opening 9 is closed by this closure disk 10.

The closure disk 10 has a spout 16 formed integral therewith. The spout is located in the region of the opening 13 and extends a slight distance beyond both sides of the opening. The center of the spout is on a line passing centrally through this opening 13. The spout inclines upwardly and outwardly at the center thereof and the side walls of the spout are curved so as to vanish into the plate at the peripheral edge thereof. When the closure disk is positioned so that the openings 9 and 13 are in register, then the spout is positioned so that it overhangs the double seam 4 and the extreme upper end of the spout is substantially on a line with the outer surface of the double seam. In this set position, the contents of the container passing through the openings into the spout, will be directed over and away from the double seam. This makes a very free pouring device for the container.

When the closure opening is turned to the position shown in full lines in Fig. 4 and in broken lines in Fig. 2, the spout is lowered so that the extreme upper edge thereof lies slightly below the plane containing the extreme upper edge of the double seam. This protects the spout and enables the containers to be stored one upon the other for handling or shipment if desired.

The side walls 6 of the depression are conical in shape so as to conform to the shaping of the spout. Furthermore, when this wall is thus shaped, the contents during dredging will not lodge on the wall 6 but will pass off from the same and into a position to pass out through the opening 9. Inasmuch as the bottom wall of the depression substantially merges into the closure end 3 at the outer edge of the opening 9, there

is no trapping of the contents of the container and substantially all of the contents may be dredged or sifted therefrom.

It is obvious that minor changes in the details of construction may be made without departing from the spirit of the invention as set forth in the appended claim.

Having thus described the invention, what I claim as new and desire to secure by Letters Patent is:

A combined pouring and sifting container comprising a body portion and closure ends seamed thereto, one of said ends having a conical depression formed therein adjacent a portion of the end seam with the bottom wall of said depression inclining upwardly toward said seam and with the extreme upper portion of said bottom wall substantially merging into the end closure, a discharge opening formed in the bottom wall of said depression at the side thereof adjacent the end seam, a disk-shaped closure plate of substantially the same diameter as the bottom wall of said depression contacting with the outer face thereof, said closure plate having a pouring opening therethrough and sifter openings at each side of said pouring opening which may be brought into register with the pouring opening in the bottom wall, a spout formed integral with said closure plate in the region of the pouring opening, said spout being shaped to conform to the conical wall of the depression and dimensioned so that when turned to the extreme position away from the end seam, the extreme outer end of the spout will be beneath the plane containing the extreme outer edge of said end seam, said spout when in pouring position being disposed so as to extend over and above the end seam, and means disposed at the center of said disk for pivotally securing said disk and spout to the end closure.
